CORE FOR ROLL PAPER PRODUCTS

James S. La Fara, Warson Woods, Mo., assignor to
Graham Paper Company, St. Louis, Mo., a corpora-
tion of Missouri

Filed Oct. 4, 1968, Ser. No. 13,842

Term of patent 14 years

Int. Cl. D6—01

U.S. Cl. D33—31

FIG. 1

FIG. 2

FIG. 4

FIG. 3

FIG. 5

FIG. 6

FIG. 7

FIG. 8

FIGURE 1 is a perspective view of a core for roll paper products embodying my new design,

FIGURE 2 is an end elevational view thereof taken from the end shown in FIGURE 1,

FIGURE 3 is an end elevational view taken from the end opposite to that shown in FIGURE 1,

FIGURE 4 is a cross sectional view taken substantially along line 4—4 of FIGURE 2,

FIGURE 5 is a perspective view of a modified form of the core for roll paper products shown in FIGURE 1,

FIGURE 6 is a cross sectional view taken substantially along line 6—6 of FIGURE 5,

FIGURE 7 is a perspective view of another modified form of the core for roll paper products shown in FIGURE 1, and

FIGURE 8 is a cross sectional view taken substantially along line 8—8 of FIGURE 7.

I claim:

The ornamental design for a core for roll paper products, substantially as shown and described.
